SUBMARINE NET

David A. Wallace, Detroit, Mich., assignor to
Chrysler Corporation, Highland Park, Mich., a
corporation of Delaware

Application May 17, 1943, Serial No. 487,225

11 Claims. (Cl. 114—241)

This invention relates to an improved submarine net.

One of the main objects of the invention is to provide a net of this character which may be collapsed in accordion-like fashion for facilitating storage in a compact form, convenience in handling during shipment and particularly during laying operations.

Another object of the invention is the provision of a net of this kind which can be built to desired length from attachable and detachable sections each comprising a complete unit.

A further object of the invention is the provision of net sections of this character which can be wound upon a reel, as is a hose, in either separate or connected condition and paid off from the reel while the latter is carried by a vessel during laying operations.

A still further object of the invention is the provision of means for connecting net sections of this kind together and to a common float line which accommodates separation of each section from the others and from the float line under the strain applied when a section of the net is engaged by a submarine.

Additional objects of the invention are to provide net sections which are built up of relatively short lengths of flexible material, such as wire, arranged in frame-like units and having eyes on their extremities loosely pivotally connected together by rings which accommodate substantially free weaving and working of successively adjacent portions of the net sections under wave action as well as accordion-like collapsing of the sections into a compact state; to provide a removable wrapper on the collapsed sections which retains the latter in a generally cylindrical shape in order to protect it during storage and shipment and to facilitate coiling it upon a reel; to provide means for retaining the wrapper in place which may be readily removed as successive connected sections are paid out from a vessel during net laying operations; and to provide tie means for temporarily holding the net sections in accordion-like contracted condition following removal of the wrapper and which are released by the action of water thereon in order to guard against complete expansion of an initially layed section of the net prior to immersion of the entire section.

A still further object of the invention is to provide on a net of this kind bombs and/or signal devices which are constructed to be exploded or actuated respectively upon contact with a submarine.

An illustrative embodiment of the invention is shown in the accompanying drawings, in which:

Fig. 1 is a fragmentary perspective view diagrammatically illustrating the improved method of laying a net embodying the invention.

Fig. 2 is a fragmentary elevational view of a pair of adjacent connected sections of a completely expanded net embodying the invention.

Fig. 3 is an enlarged fragmentary view of the structures encompassed by the circle A in Fig. 2.

Fig. 4 is an enlarged fragmentary view of the structure encompassed by the circle B in Fig. 2.

Fig. 5 is a fragmentary perspective view illustrating the manner of attachment of a pair of net sections embodying the invention.

Fig. 6 is a fragmentary perspective view of a wrapped net embodying the invention illustrating the compact condition thereof.

Fig. 7 is an elevational view of the improved net showing the latter in accordion-like contracted state preparatory to rolling it to cylindrical form.

Fig. 8 is a fragmentary elevational view of a submarine net embodying a modified form of the invention.

Fig. 9 is a sectional view of a binding tape element shown in Fig. 5.

Fig. 10 is a fragmentary perspective view similar to Fig. 1, but illustrating a modified net laying operation.

In the form of the invention shown in the drawings my improved submarine net comprises a plurality of net sections A and B each of which are of substantially identical construction. Each net section comprises a plurality of horizontally extending rows of wire bars 12 and a plurality of vertically extending rows of wire bars 13 located at the junctions of the bars 12 of the horizontal rows. The wire bars 12 and 13 preferably comprise high carbon steel wire having a high tensile strength of the order of 300,000 pounds per square inch. These bars are flexibly connected together at their adjacent end portions by rings 14. Each end of each bar is attached to a ring

14 in any suitable manner which will permit limited pivotal and shifting movement of the end of the bar with respect to the ring 14. As illustrated in Fig. 4, the end portion of each wire bar is preferably wrapped twice about the ring and then several times about the standing part of the bar, thus forming a secure connection which is characterized by the required flexibility.

Extending along the uppermost horizontal row of bars 12 is a float line generally designated by the numeral 15 which comprises a rope or cable

16 on which float elements 17 are threaded. Attached to each ring 14 of the upper row of horizontal bars 12 is a chain member 18 having a parting link 19 therein which is connected by a link 20' with the cable 16 of the float line. The parting links 19 are adapted to open when subjected to a predetermined stress so as to permit separation of each net section A and B from the float line 15 in the manner hereinafter set forth. Each of the vertical rows of wire bars 13 forming the longitudinal extremities of the net sections A and B are provided with connecting link members which include relatively shorter wire bars 20. A wire bar 20 is flexibly connected to each of the rings of the row of bars at each longitudinal extremity of the net in the manner described above and illustrated in Fig. 4. A ring 21 is preferably flexibly connected in a similar manner to the opposite end of each wire bar 20. The rings 21 are detachably connected together by an S-shaped parting clip 22 which, like the parting links 19, is adapted to open when subjected to a predetermined strain in order to permit separation of one net section from another. Attached to the outer end of each vertically extending row of bars 13 is a weight member 23 which is adapted to cooperate with the float line 15 in retaining the net sections suspended in water in a vertically upright position as illustrated in Fig. 2.

Nets of the foregoing construction may be used to support bombs, such as illustrated at 24, which preferably have a discharging trigger ring 25' adapted to explode the bomb when contacted by an object such as a submarine. The bombs 24 are preferably suspended within selected squares formed by bounding bars 12 and 13 and in such position that swinging movement of the bomb will not bring its trigger into contact with any of the bars.

Nets of the foregoing construction may be used for discharging signals such as a luminous signal flare 25 which is adapted to float upon the surface of the water and to be ignited when a submarine comes in contact with the net. If the net is provided with parting clips and rings 22 and 19 respectively, then upon a submarine encountering one section of the net, that section will be torn away from the floating line 15 and from the other net sections. If the flare signal 25 is attached to the float line by a cable 26 and has a trigger mechanism (not shown) attached to the net section A by a cable 27, then, upon separation of the net section from the float line 15, the trigger mechanism of the flare signal will be actuated to ignite it. By employing a parting clip to connect one of the cables 26 and 27, and a permanent means to connect the other to the net section or float line, the signal can be caused to remain attached to either the net section or float line as desired. Any desired type of signalling device may be used for this purpose, and if it is not desired to have one net section become separated from the others and from the float line when a submarine engages it, then the parting links and parting clips 20' may be substituted for by more permanent connecting means. It should be understood that a plurality of signalling devices may be carried by each net section and a plurality of bombs may likewise be supported thereby.

One of the main obstacles encountered in submarine protection by nets is the difficulty of storing such nets and transporting and laying them, for they are a cumbersome contraption.

With applicant's improved submarine net, the flexibly connected wire bar structure permits a net to be collapsed in accordion-like fashion, as illustrated in Fig. 7, by pulling adjacent horizontally extending rows of wire bars in respectively opposite directions. When a net embodying applicant's invention has been so collapsed, it may be conveniently rolled into a cylindrical condition resembling a fire hose in both size and shape. A collapsed and rolled net section may be readily wrapped with a protecting covering 28 as illustrated in Fig. 5. Each section is preferably individually wrapped so as to leave the wire bar members 20 with their end rings 21 exposed for attachment to corresponding wire bars of the next successive net section. The rings 21 of the adjacent ends of the sections may be tagged so as to facilitate convenient coupling of one net section to another. The collapsed, rolled and wrapped net sections may be conveniently stored in piles on the deck of a boat and connected together as they are laid in the water, or such net sections may be connected together with the junction therebetween shielded by a wrapping 29 illustrated in Fig. 6. A plurality of connecting net sections, such as illustrated in Fig. 6, may be conveniently wound upon a drum 30 mounted on the stern of a boat from which the net may be conveniently laid. The wrappings 28 and 29 may be temporarily bound in place by wire or cord binding members 31 which may be cut as the successive rolled net sections are fed from the stern of a boat as illustrated in Fig. 1. However, if desired, the wrappings 28 and 29 may be held in place, as illustrated in Fig. 5 by releasable binding members, each of which comprises a water soluble tablet 31, preferably formed of compressed sodium chloride. Each salt tablet is provided with a pair of apertures 32 through which one end of a cord 33 extends, there being a knot 34 formed at each extremity of the cord 33. When a wrapped net is held in rolled state by releasable binding members of the foregoing type, the net may be fed from the stern of a boat, as illustrated in Fig. 10 and floated upon the surface of the water. After a predetermined length of time, the salt tablets 31 dissolve, releasing the wrapping and permitting unrolling and expansion of each net section to a vertically suspended position under the action of its weight member 23. If desired, the wrappings 28 and 29 may be omitted and the releasable binding members, shown in Fig. 6 may be employed to tie the net sections in rolled condition. In some instances, it is desirable to allow the net to unroll following a predetermined time interval after the net has been deposited in the water, but to hold it from expanding until a later time. This may be accomplished as illustrated in Fig. 8 by threading a line extending from the float line through each vertically disposed row of rings 14 and tying the end thereof to a salt block 35 which is too large to pass through the rings. When the salt block 35 dissolves, the rings 14 are released from their contracted position, shown in Fig. 8, and the net is thus permitted to expand to the state illustrated in Fig. 2. In some net laying operations, it may suffice to merely hold the net sections in the contracted condition illustrated in Fig. 8 without rolling each net section into hose-like cylindrical form. Plastic cord which dissolves after exposure to water for a predetermined length of time may be used as ties if desired.

Submarine nets conforming to the foregoing

construction comprise wire of relatively small diameter which is flexible and which does not present much resistance to the wave action of the sea. They can be brought to any desired length, merely by adding or subtracting the required number of net sections. With nets of this construction, the problems encountered in storage, shipment and laying operations are greatly simplified and only one vessel is required to deposit the nets in a selected location. Nets of this character may readily be removed from the sea, collapsed in continuous form or as individual sections, and relaid in another location after transportation.

Although but several specific embodiments of the invention are herein shown and described, it will be apparent that various changes in the size, shape and arrangement of parts may be made without departing from the spirit of the invention.

I claim:

1. A submarine net comprising an upper line member having a plurality of float elements thereon, and a net structure attached along one of its extremities to and adapted to depend from said upper member comprising a plurality of net sections each including a multiplicity of wire bars arranged in polygonal formation, the side of each polygon of said formation comprising an individual wire bar, means universally shiftably connecting the adjacent extremities of the bars of each polygon together and to the extremities of the bars of adjacent polygons, weight means attached to said net structure along the opposite extremity thereof, and a plurality of parting clips connecting the upper sides of each section to said upper line member and connecting the lateral sides of said sections together, said parting clips being adapted to open when subjected to a predetermined strain for accommodating separation of one or more sections from the others of said net when a submarine contacts therewith.

2. A submarine net including an upper float line member, a net member suspended from said float line member comprising a plurality of net sections each having a weight member secured at its lower extremity, a plurality of parting clips connecting the upper sides of said net sections to said float line member and connecting lateral sides of adjacent sections together, said parting clips being adapted to open under a predetermined strain for accommodating separation of one or more sections from the others when a submarine contacts therewith, and a signal device attached to one of said members having an actuating cable attached to the other member for exciting said signal device when a section of said net is so separated from the remaining sections.

3. A submarine net section comprising a plurality of longitudinally and laterally extending rows of wire bars, one laterally extending row of bars being disposed at the extremities of each bar of said longitudinally extending rows, means for flexibly connecting together the adjacent ends of the bars of said longitudinally and laterally extending rows to accommodate collapsing of said net section in accordion-like fashion by relatively displacing adjacent longitudinal rows in respectively opposite directions, said net section when so collapsed being adapted to be rolled into substantially cylindrical formation, a removable wrapper for surrounding said net section when so rolled in order to protect the same during storage, shipment and laying operations and

means for releasably holding said wrapper in place including a self-releasing member adapted to accommodate displacement of said wrapper from said net section after the latter has been laid.

4. A submarine net section comprising a plurality of longitudinally and laterally extending rows of wire bars, one laterally extending row of bars being disposed at the extremities of each bar of said longitudinally extending rows, a float line member extending along one longitudinal edge of said net section and attached to the latter, a weight member extending along the opposite longitudinal edge of said net section and attached thereto, means for flexibly connecting together the adjacent ends of the bars of said longitudinally and laterally extending rows to accommodate collapsing of said net section in accordion-like fashion by relatively displacing adjacent longitudinal rows in respectively opposite directions, said net section when so collapsed being adapted to be rolled into substantially cylindrical formation, a removable wrapper for surrounding said net section when so rolled in order to protect the same during storage, shipment and laying operations and means for releasably holding said wrapper in place comprising a self-releasing water soluble element adapted to accommodate displacement of said wrapper and expansion of said net section after the latter has been immersed in water for a predetermined period.

5. A submarine net section comprising a plurality of longitudinally and laterally extending rows of wire bars, one laterally extending row of bars being disposed at the extremities of each bar of said longitudinally extending rows, a float line member extending along one longitudinal edge of said net section and attached to the latter, a weight member extending along the opposite longitudinal edge of said net section and attached thereto, means for flexibly connecting together the adjacent ends of the bars of said longitudinally and laterally extending rows to accommodate collapsing of said net section in accordion-like fashion by relatively displacing adjacent longitudinal rows in respectively opposite directions, said net section when so collapsed being adapted to be rolled into substantially cylindrical formation, a removable wrapper surrounding said rolled net section for protecting the same during storage, shipment and laying operations, and connecting members on the free extremities of the bars of said longitudinally extending rows along one end of said net section, said connecting members protruding from said wrapping for facilitating attachment of each longitudinally extending row of bars of said net section to a corresponding row of another net section.

6. A submarine net comprising a plurality of longitudinally aligned net sections each including a plurality of longitudinally and laterally extending rows of individual wire bars arranged in end to end alignment, one laterally extending row of bars being disposed at the extremities of each bar of said longitudinally extending rows, means universally shiftably connecting together adjacent extremities of the individual bars of said longitudinally and laterally extending rows thereof, a float line member disposed adjacent one longitudinal edge portion of each net section, means including parting clips connecting said latter edge portion of each section to said float line member, a weight member attached to the

opposite longitudinal edge portion of each net section, and means including parting clips on the ends of the corresponding longitudinally extending rows of bars of each section for separably connecting adjacent ends of said sections together.

7. A submarine net comprising a plurality of longitudinally aligned net sections each including a plurality of longitudinally and laterally extending rows of wire bars, one laterally extending row of bars being disposed at the extremities of each bar of said longitudinally extending rows, means for flexibly connecting together the adjacent ends of the bars of said longitudinally and laterally extending rows to accommodate collapsing of said net sections in accordion-like fashion, said net sections when so collapsed being adapted to be rolled into substantially cylindrical formation, a float line member extending along one edge portion of each net section, means connecting said edge portion of each section with said float line member, a weight member attached to the opposite edge portion of said net section, means connecting the ends of corresponding longitudinal rows of bars of each section, a removable wrapper surrounding the rolled net for protecting the latter during storage, shipment and laying operations and automatically releasable means for releasably holding said wrapper in place adapted to release the same after said net has been laid for a predetermined period.

8. A submarine net comprising a plurality of longitudinally aligned net sections each including a plurality of longitudinally and laterally extending rows of wire bars, one laterally extending row of bars being disposed at the extremities of each bar of said longitudinally extending rows, means for flexibly connecting together the adjacent ends of the bars of said longitudinally and laterally extending rows to accommodate collapsing of said net sections in accordion-like fashion, said net sections when so collapsed being adapted to be rolled into substantially cylindrical formation, a float line member extending along one longitudinal edge portion of each net section, parting clips connecting said latter edge portion of each section to said float line member, a weight member attached to the opposite longitudinal edge portions of said sections, parting clips on the ends of the corresponding longitudinal extending rows of bars of each section for separably connecting adjacent longitudinal ends of said sections together, a removable flexible wrapper surrounding each of said rolled net sections, a removable flexible wrapper overlapping the extremities of the wrappers of said net sections and surrounding the connections therebetween, said wrappers being adapted to protect said net sections and connections against injury during storage, shipment and laying operations and said net when in rolled and wrapped state being adapted to be wound on a drum.

9. A submarine net comprising a plurality of

longitudinally aligned net sections each including a plurality of longitudinally and laterally extending rows of wire bars, one laterally extending row of bars being disposed at the extremities of each bar of said longitudinally extending rows, means for flexibly connecting together the adjacent ends of the bars of said longitudinally and laterally extending rows to accommodate collapsing of said net sections in accordion-like fashion, means for releasably holding said net sections in collapsed state, said net sections when so collapsed being adapted to be rolled into substantially cylindrical formation, a float line member disposed adjacent one longitudinal edge portion of each net section, means connecting said edge portion of each section and said float line member, a weight member attached to the opposite edge portion of each net section, means connecting the ends of corresponding longitudinal rows of bars of each section, and a removable wrapper surrounding the rolled net for protecting the latter during storage, shipment and laying operations.

10. A submarine net section comprising a plurality of longitudinally and laterally extending rows of wire bars, one laterally extending row of bars being disposed at the extremities of each bar of said longitudinally extending rows, means for flexibly connecting together the adjacent ends of the bars of said longitudinally and laterally extending rows to accommodate collapsing of said net section in accordion-like fashion by relatively displacing adjacent longitudinal rows in respectively opposite directions, said net section when so collapsed being adapted to be rolled into substantially cylindrical formation and releasable binding members for holding said net in rolled state each comprising a water soluble link element adapted to dissolve after said net has been immersed in water for a predetermined period for accommodating unrolling and expansion of the latter without manual manipulation.

11. A submarine net comprising a plurality of longitudinally aligned net sections each including a plurality of longitudinally and laterally extending rows of wire bars, one laterally extending row of bars being disposed at the extremities of each bar of said longitudinally extending rows, means for flexibly connecting together the adjacent ends of the bars of said longitudinally and laterally extending rows to accommodate collapsing of said net sections in accordion-like fashion, means for releasably holding said net sections in collapsed state including a water soluble element adapted to dissolve after immersion in water for a predetermined period in order to automatically accommodate expansion of said net sections, a float line member extending along and attached to one longitudinal extremity of each net section, and a weight member attached to the row of bars of each section extending along the opposite longitudinal extremity thereof.

DAVID A. WALLACE.
